DESIGN FOR A GIRL'S CLOAK.

SPECIFICATION forming part of Design No. 14,367, dated October 23, 1883.

Application filed August 23, 1883. Term of patent 3½ years.

UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A GIRL'S CLOAK.

SPECIFICATION forming part of Design No. 14,367, dated October 23, 1883.
Application filed August 23, 1883. Term of patent 3½ years.

To all whom it may concern:

Be it known that I, CATHERINE O'HARA, of the city, county, and State of New York, have invented and produced a new and original Design for a Pattern of a Girl's Cloak, (numbered 8,830;) and I do hereby declare that the engraved print accompanying this specification conveys to any one accustomed to using paper patterns a clear understanding of how a garment made up by the pattern will appear.

The design combines sack-fronts buttoned all the way down, a half-fitted back with a

double box-plait down its center, cape-sections extending from beneath the box-plait, a 15 rolling collar, coat-sleeves, and pocket-laps.

What I claim as my invention, and desire to secure by Letters Patent, is—

The design for a girl's cloak, as shown in the engraved print accompanying this specification.

CATHERINE O'HARA.
